UNITED STATES PATENT OFFICE.

JOSEPH BENJAMIN, OF CHICAGO, ILLINOIS.

REFLECTOR.

No. 906,096.

Specification of Letters Patent.

Patented Dec. 8, 1908.

Application filed August 28, 1907. Serial No. 390,525.

To all whom it may concern:

Be it known that I, JOSEPH BENJAMIN, a citizen of the United States, residing at Chicago, in the county of Cook and State of Illinois, have invented a new and useful Reflector, of which the following is a specification.

This invention relates to reflectors for incandescent lamps.

10 The object of this invention is to provide a reflector of the above character which shall combine simplicity of construction, high efficiency and durability in use, and beauty and attractiveness in appearance.

15 With the above and other objects in view as will appear as the nature of the invention is better understood, the same consists in the novel features of construction of a reflector for incandescent lamps as will be hereinafter 20 fully described and claimed.

25 In the accompanying drawings forming a part of this specification, and in which like characters of reference indicate corresponding parts, Figure 1 is a plan view of the support or backing of the reflector. Fig. 2 is a fragmentary detail view exhibiting a portion of the finished reflector. Fig. 3 is a transverse sectional view through the reflector embodying the backing shown in Fig. 1, the 30 section line being taken through the center of the structure. Fig. 4 is a transverse sectional view taken on the line 4—4 of Fig. 1. Fig. 5 is a transverse sectional view through a modified form of the invention.

35 Referring to the drawings, 1 designates the backing of the reflector which has secured to or formed on one face any suitable design that may be desired; that herein shown consisting of a sixteen pointed star, the rays 2 of 40 which are, as shown in Fig. 4, angular in cross section. The backing 1 may be made of any suitable material such as pasteboard, stamped metal or the like, and where either of these latter materials are employed the 45 star or other design will be an integral portion thereof.

In the form shown in Fig. 1, the backing and star are of wood, and the backing is preferably made of a plurality of sections and the 50 star of sections of wood glued or otherwise secured to the backing. At the center of the backing is an opening 3 to receive the shank of an electric light bulb. The rays of the stars, that is to say, their inclined faces, have 55 attached to them strips of mirror 4 that are ground in such manner that their meeting

edges will be practically invisible, thus to add to the ornamental appearance of the device. Between the points of the rays are secured ornamental tiles 5, of any preferred material, either of metal or vitreous material, and of any color that will enhance the beauty of the article as a whole. The backing is herein shown as circular and this will generally be its preferred form; but it may be 65 of other shapes and still be within the scope of the invention. The periphery of the backing has secured to it a beading 6 of any suitable material, and this will add materially to the esthetic effect produced by the device. 70

The form of the invention shown in Fig. 5 is intended to represent a backing made of any compressible material such as pasteboard or metal, or of cast metal, wherein the angular protuberances 7 will be the rays of 75 the stars and the portions 8 the attached mirrors.

The backing can be made of any material that can be molded or formed for the purpose, such as cement, plaster of paris, earthy 80 materials and the like. The reflector is also to be used for any style of lamp or for electric lights, and can be placed upon ceilings, walls or in any other position where ordinary lights are located. 85

The article is simple of construction, and may be readily manufactured without the employment of a particular machine for the purpose and by providing the backing and the tiles with orifices 9 and 10, respectively, 90 that register, the article may be firmly secured to the ceiling of a room.

What is claimed is:

1. A reflector comprising a flat backing having one side defining an outstanding design, presenting angular surfaces, mirrors attached to said surfaces, and reflecting tiles arranged around the design, said mirrors and tiles being arranged to form uninterrupted reflecting surfaces. 100

2. A reflector comprising a flat backing having its face defining a many pointed star, the rays of which are angular in cross section, mirrors attached to the faces of the rays, and reflecting tiles secured between the points of 105 the rays, said mirrors and tiles being arranged to form uninterrupted reflecting surfaces.

3. A reflector comprising a flat backing provided with orifices and having one face defining a many pointed star, the rays of 110 which are angular in cross section, mirrors secured to the faces of the rays, and reflecting

5 tiles secured between the points of the rays and having orifices to register with those of the backing, said mirrors and tiles being arranged to form uninterrupted reflecting surfaces, said orifices being adapted to receive attaching means.

4. A reflector comprising a flat backing provided with orifices for attaching means and having one face defining an outstanding 10 star shaped design, presenting angular surfaces, mirrors attached to the surfaces, reflecting tiles arranged between the points of the star, and extending to the periphery of

the backing, and reflecting beading inclosing the periphery of the backing and the outer 15 ends of the tiles, said mirrors, tiles and beading being arranged to form uninterrupted reflecting surfaces.

In testimony that I claim the foregoing as my own, I have hereto affixed my signature 20 in the presence of two witnesses.

JOSEPH BENJAMIN.
